UNITED STATES PATENT OFFICE

172,683

HOBBYHORSE

Joseph Piacente, Chicago Heights, Ill., assignor
to Bronco Horse Company, Chicago Heights, Ill., a corporation of Illinois

Application April 17, 1953, Serial No. 24,551

Term of patent 3½ years

(Cl. D34—15)

To all whom it may concern:

Be it known that I, Joseph Piacente, a citizen of the United States, residing at Chicago Heights, in the county of Cook and State of Illinois, have invented a new, original, and ornamental Design for a Hobbyhorse, of which the following is a specification, reference being had to the accompanying drawing, forming a part hereof.

Fig. 1 is a perspective view of a hobbyhorse,
showing my new design; and,

Fig. 2 is a perspective view thereof, to an enlarged scale, showing the side opposite that shown in Fig. 1.

I claim:

The ornamental design for a hobbyhorse, as shown.
